UNITED STATES PATENT OFFICE.

ALMOND B. GREEN, OF FULTON, OHIO.

WRENCH.

SPECIFICATION forming part of Letters Patent No. 739,490, dated September 22, 1903.

Application filed June 19, 1903. Serial No. 162,264. (No model.)

To all whom it may concern:

Be it known that I, ALMOND B. GREEN, a citizen of the United States, residing at Lyons, in the county of Fulton and State of Ohio, have invented certain new and useful Improvements in Wrenches; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in sliding-jaw wrenches; and it consists in the provision of a fixed jaw having a handle with a serrated edge and a spring-bar which is carried by the shank portion of the fixed jaw, one end of the spring bearing against the fixed jaw and the other end being seated in a notch in the shank portion, while the straps on the sliding jaw pass about the spring, which holds a lug on the movable jaw in engagement with the serrations.

The invention consists, further, in various details of construction and combinations and arrangements of parts, which will be herein-after fully described and then specifically defined in the appended claims.

My invention is clearly illustrated in the accompanying drawings, in which—

Figure 1 is a side elevation of my improved wrench. Fig. 2 is a central longitudinal section through the wrench.

Reference now being had to the details of the drawings by letter, A designates a fixed jaw having a shank portion A', one edge of which is serrated, as at B. A handle C is fitted on said shank portion, and one edge of said shank portion is notched or recessed out, as at D, adjacent to the handle, and E designates a spring-bar, one end of which is seated in said recess and engages within the hole in the handle, which receives the shank portion, thereby securely anchoring one end of said spring, while the other end of the spring engages the head of the fixed jaw at a. Said spring normally is in a bowed or arched position, as shown in the drawings, and F designates a sliding jaw, which is chambered out and has a tapering steel lug H fitted within the same, the angled edge of

which is adapted to engage the teeth or serrations on said shank portion. The straps 55 F' on the movable jaw surround the shank portion of the fixed jaw and also said spring E, and said sliding jaw is held by the spring so that the lug H will be in a locked relation.

When it is desired to move the jaw F, the 60 operator by depressing upon the straps F' will cause the spring to yield and the lug to disengage from the notches, after which the jaw F' may be moved toward the fixed jaw or away therefrom, adjusting the same for 65 various uses.

While I have shown a particular construction of wrench embodying my invention, it will be understood that I may make alterations in the detailed construction of the same 70 without departing from the spirit of the invention.

Having thus fully described my invention, what I claim as new, and desire to secure by Letters Patent, is—

1. A sliding-jaw wrench, comprising in combination with the fixed jaw and shank portion with serrations thereon, a spring-bar, one end of which bears against said fixed jaw, its other end seated in a recess in the 80 edge of said shank portion, and a movable jaw having straps surrounding said shank portion, a projection on said movable jaw designed to engage the teeth on said shank portion and held in locked position by means of 85 said spring, as set forth.

2. A wrench having a fixed jaw with a shank portion having serrations on one of its edges, and having a notch on the edge opposite the serrations, a spring-bar having an 90 angled portion seated in said notch, a handle fitted over the end of said spring-bar and notch, the other end of the spring bearing against the fixed jaw, a sliding jaw having straps fastened about the shank portion of 95 the fixed jaw, and an angled lug fitted within the movable jaw and adapted to be held by said spring in engagement with the teeth of said shank portion, as set forth.

In testimony whereof I hereunto affix my 100 signature in presence of two witnesses.

A. B. GREEN.
